Primary Examiner—Sandra L. Morris*Assistant Examiner*—Richelle Shelton*Attorney, Agent, or Firm*—Parsons & Goltry; Robert A. Parsons; Michael W. Goltry[57] **CLAIM**

The ornamental design for a hand held masking device frame, as shown and described.

DESCRIPTION

FIG. 1 is a perspective view of a hand held masking device frame, showing my new design therefor;

FIG. 2 is a top plan view of the hand held masking device frame;

FIG. 3 is a left side elevational view of the hand held masking device frame;

FIG. 4 is a front view of the hand held masking device frame;

FIG. 5 is a rear view of the hand held masking device frame;

FIG. 6 is a bottom plan view of the hand held masking device frame; and,

FIG. 7 is a right side elevational view of the hand held masking device frame.
